DESIGN FOR A MULTIPLE YARN SPOOL HOLDER

Walter Eskowski, Milwaukee, Wis.

Application July 28, 1939, Serial No. 86,297

Term of patent 3½ years

To all whom it may concern:

Be it known that I, Walter Eskowski, a citizen of the United States and a resident of Milwaukee, in the county of Milwaukee and State of Wisconsin, have invented a new, original, and ornamental Design for Multiple Yarn Spool Holders, of which the following is a specification, reference being had to the accompanying drawing, forming part thereof.

The figure is a perspective view of a multiple yarn spool holder, showing my new design.

I claim:

The ornamental design for a multiple yarn spool holder, as shown.

WALTER ESKOWSKI.
